UNITED STATES PATENT OFFICE.

WILLIAM E. WINE, OF TOLEDO, OHIO.

RAILWAY CAR.

Application filed June 23, 1921. Serial No. 479,723.

To all whom it may concern:

Be it known that I, WILLIAM E. WINE, a citizen of the United States, residing at Toledo, in the county of Lucas and State of Ohio, have invented certain new and useful Improvements in Railway Cars, of which the following is a specification.

This invention relates to railway cars, and has among its objects to provide an improved arrangement of drop door mechanism for the same. Another object is to provide a simple method of supporting the doors from the car structure and of positively locking them in closed positions.

With these general objects in view, the invention consists of the formation, combination and arrangement of parts as will be herein described and particularly claimed.

In the accompanying drawings, which show a preferred embodiment of the invention,—

Figure 1 is a diagrammatic view showing in side elevation a portion of a railway car having drop doors arranged for the use of the present mechanism.

Figure 2 is an enlarged fragmentary view of the side of a car showing one of the drop doors with the locking mechanism associated therewith.

Figure 3 is a transverse vertical section taken through a portion of the car and through one of the drop doors.

Referring to these drawings, the side of the car which is shown as constructed of horizontally arranged side planking, is denoted by the numeral 1. Immediately beneath the side planking is a metal side sill 2, which is formed of a structural steel channel with the back of the same substantially on line with the inside face of the side planking, the web being vertical and the horizontal flanges located beneath the bottom edge of the side planking and outstanding away from the center of the car. The car may have a center sill constructed of the customary plate and channel type, as designated by the numeral 3, on top of which may be arranged a portion of the floor planking 4.

Secured as by riveting to the center sill construction are door hinges, such as 5, and to these are swingingly attached one or more drop doors, such as 6. The drop doors extend from the center sill construction to the side of the car and are arranged to swing

about an axis parallel with the center sill of the car, or in other words, to swing transversely of the car, thereby providing for the discharge of the lading to a point alongside of the track.

The door in the present construction is formed of door planks 7 supported upon battens 8. A reinforcing hinge strap 9 passes beneath the planking and extends inward to the pivoted edge of the door where it is formed in loop fashion as at 10 to provide the door portion of the hinge. At the outer or free edge of the door this reinforcing member extends slightly outside of the lines of the car side and is there formed in loop fashion, as at 11, to provide an accessible extension or hand hold for lifting the door, and also to provide a locking face for the engagement of the door supporting hooks when the door is in closed position. This location of the locking hook also makes it easy to release the doors. It will be understood that a plurality of these hinge members, preferably two, are furnished for each door, and they are arranged in spaced relationship with each other so as to properly support the door and to provide a reasonable hinge spacing. One of the brackets 5 should be provided upon the center sill for each of the door hinge members 9.

A gravity actuated door hook member, such as 12, is pivoted upon the side sill 2 for each of the members 9. These are arranged to swing longitudinally of the car, or at right angles to the swing of the door, about pivot points 13 and just outside of and along the edge of the lower flange of the channel 2. These hooks, as well as their brackets now to be described, are positioned so that the hooks will face in the opposite directions; that is, the hooks when forced to their supporting position will swing towards the members 9 and away from each other. The positioning of these hooks to swing in the opposite directions is important and the benefits derived will be described more in detail as the specification proceeds. A bracket, such as 14, is provided for each hook 12. The said bracket preferably includes an inner plate member having projections which extend back into the cavity of the channel so as to space the outer face of the said plate in substantial alignment with the outer edge of the lower flange of the said channel. The brackets 14 are

- riveted to the web of the channel 2 in order to simplify the problem of removal for repairs. A hook retaining cam 15 is also pivoted to each of the brackets 14 to prevent the accidental release of the hook 12. When this cam, which is eccentric in shape, is rotated about its pivot 16 in one direction it allows the hook 12 to be driven out of position beneath the portion 11 of the hinge member 9. When the hook is in position beneath the projection 11 for supporting the door, the cam 15 may be rotated in the proper direction to engage the back of the hook and hold it in position. The looped ends 11 of the members 9 serve to limit or arrest by direct contact therewith the movement of each hook in one direction. Thus when each hook is locked by the rotation of the cam 15 pivotal movement in one direction is prevented by the engagement of the hook with the hinge extension or arm 11, and pivotal movement of the hook in the opposite direction is prevented by its locking cam.
- 25 A retaining plate 17, corresponding in outline to the plate of the bracket 14, may be applied over the hook 12 and cam 15 of each bracket, the rivets coincident with the pivot points 13 and 16, as well as an additional rivet 18, passing through this plate and through the plate of the bracket 14 and the channel 2, thereby economically tying all of these parts together and producing a compact arrangement and one especially suited to rough service. The door is thus supported at both edges upon corresponding members, namely, the hinge members 9, so that the forces are largely restricted and concentrated in these members.
- 40 The looped ends 11 of the members 9 are arranged to slightly overreach the free edge of the door and there constitute, as hereinbefore stated, both handholds and hook-engaging arms for cooperation with the swinging hooks 12. It will be noted that the free edge of the door falls approximately on line with the outer edge of the flange of the channel 2, and the looped ends or extensions 11 extend out beyond the lines of the door edges and outside of the lines of the channels. By extending the free edge of the door to and under the side sill 2 I obtain the maximum door opening, and in addition it will be seen that the door is supported not upon the floor of the car but upon the longitudinal framework thereof, that is, at opposite ends upon the center and side sills, the hinged edge of the door being supported upon the center sill and the swinging edge 55 upon the side sill. This construction relieves the floor proper from load and all vibration which would otherwise result from the support of the doors thereupon.
- 60 As heretofore noted, each door is supported by a plurality of swinging hook mem-
- bers 12 which are applied to the car side so as to swing in opposite directions. By thus arranging the hooks and particularly in a construction in which the plane of movement of the hooks is parallel with the longitudinal axis of the car the effect of end shocks to which cars are subjected in service are neutralized. Among the advantages which flow from this construction may be mentioned the following: first, any end shock which tends by the inertia of either the hook or the door or by the hook lock or cam to release one of the hooks, will automatically, by reason of the other hook facing in the opposite direction, tend to tighten this oppositely arranged or companion hook, thus ensuring at all times that at least one of the two hooks by which each door is fastened will be in engagement with the door arm 11. Second, by reason of the hooks facing in opposite directions all parts of the door and door mechanism will be tightly locked against vibration when the hooks are driven home from opposite directions. Third, the door will be held in its normal position with respect to the door opening in the car floor and the weave of the car side with respect to the center sill will be prevented. Fourth, when the hooks are forced to locked position and maintained in this position by means of the cams 15, it will be seen that each door will be held against slippage either from hinge clearance or other relative movement between the door and the car body which might occur from shocks or impacts incident to service.
- 50 The invention just described is particularly applicable to old cars of the wooden type, although it may be employed to advantage in many of the most modern forms of cars. The doors as constructed and arranged are of a very simple character and the mechanism for supporting them is economical in first cost and positive in operation. It is not contemplated to supply any winding mechanism for lifting the doors as it has been found from experience that this can be readily done by hand, so that many of the disadvantages incident to door operating devices are avoided in the present construction.
- 55 Having thus described my invention, what is claimed is:
1. In a door device for railway cars, a door hinged to the car body, with the door pintles arranged longitudinally of the car, a pair of door-supporting members pivoted upon the car body and arranged to cooperatively engage portions of the door to retain the same in closed position, the said members being disposed in opposite directions with respect to each other and being arranged to cooperate between the door and the car body in such manner that one of said members will arrest the door against slippage longi-

tudinally of the car, in one direction and the other against such slippage in the opposite direction.

2. In a door device for railway cars, a door hinged to the car body, a pair of door-supporting members pivoted upon the car body and arranged to cooperatively engage portions of the door near the free edge of the same to retain the door in closed position, the said members being arranged to swing from opposite directions into engagement with the doors, said door cooperating with the door-supporting members for limiting the swing of the door-supporting members in one direction, and means cooperating between the door-supporting members and the car body for holding the said door-supporting members against movement in the opposite directions.

3. In a door device for railway cars, a door hinged to the car body with the pintles thereof lying longitudinally of the car, a pair of brackets affixed to the door and overlying the free edge of the same, one near each end thereof, a pair of door-supporting hooks pivoted upon the car body and arranged to swing in opposite directions into engagement with the said brackets, and means for holding the hooks in engagement with their respective brackets.

4. In a door device for railway cars, a door hinged to the car body, a pair of brackets affixed to the door and over-reaching the free edge of the door, one near each end thereof, a pair of door-supporting hooks pivoted upon the car body and arranged to swing substantially at right angles to the swing of the door and in opposite directions from each other into engagement with the said brackets, and means for holding the hooks in engagement with their respective brackets.

5. The combination with a railway car having a center sill extending longitudinally of the car near the center thereof, of a door hinged in the floor of the car along one side of the center sill, the free edge of the door being arranged to be swung into a closed position along the side of the car, a pair of brackets carried by the door and extending outwardly therefrom beneath the side of the car, a pair of door-supporting hooks pivoted upon the side of the car, one arranged for supporting cooperation with each of the said brackets, the said hooks being arranged to swing from opposite directions into engagement with the respective brackets, and means co-acting between the hooks and the side of the car for holding the hooks in engagement with the brackets.

6. In a door device for railway cars, a door hinged to the car body with the door pintles arranged longitudinally of the car, said door being provided with a plurality

of portions projecting from the free end of said door, and means for retaining the said door in closed position, said means comprising a pair of independently movable members, each of said members being adapted to engage one of said projections, said members being movable in opposite directions to release said door.

7. In a door device for railway cars, a door hinged to the car body and furnished with a plurality of arms projecting from the free edge opposite said hinge and intermediate the side edges thereof, and a pair of hook members carried by said car and each adapted to engage one of said arms, said hooks being movable in opposite directions to disengage the same from said arms, and means for releasably maintaining said hooks in engagement with said arms.

8. In a door device for railway cars, a door hinged along one of its edges to the car body, means for releasably holding the opposite edge of said door adjacent a fixed portion of said car body, said means comprising a pair of members carried by said door and a pair of oppositely arranged gravity actuated members carried by said car body, said last named members being adapted to respectively engage said door members and being movable in opposite directions to release said door, and means for releasably maintaining said gravity actuated members in holding position.

9. In a door device for railway cars, a door supported at one edge on the car body, means for releasably maintaining the opposite edge of said door adjacent a fixed portion of said car, said means comprising a pair of members connected to said door and a pair of oppositely arranged gravity actuated members carried by said car, said last named members being adapted to engage the former, and means for holding said gravity actuated members in engagement with said door members.

10. In a door device for railway cars, a door hinged to the car body with the door pintles arranged longitudinally of the car, said door being provided with a plurality of portions projecting from the edge opposite said pintles, and means for retaining said door in closed position, said means comprising a pair of independently movable gravity actuated members, said members being adapted when in engagement with said projecting portions of said door to hold the latter from longitudinal movement with respect to said car, and separate means cooperating with each of said members for retaining the same in engaging position.

In testimony whereof I affix my signature.

WILLIAM E. WINE.
